A. F. & F. C. EAGLESTON.
RAILWAY RAIL FASTENER.
APPLICATION FILED JAN. 23, 1914.

1,121,338.

Patented Dec. 15, 1914.

UNITED STATES PATENT OFFICE.

ALBERT F. EAGLESTON AND FLOYD C. EAGLESTON, OF MANBAR, WEST VIRGINIA.

RAILWAY-RAIL FASTENER.

1,121,338.

Specification of Letters Patent. Patented Dec. 15, 1914.

Application filed January 23, 1914. Serial No. 813,948.

To all whom it may concern:

Be it known that we, ALBERT F. EAGLESTON and FLOYD C. EAGLESTON, citizens of the United States, residing at Manbar, in the county of Logan and State of West Virginia, have invented certain new and useful Improvements in Railway-Rail Fasteners, of which the following is a specification.

This invention relates to improvements in devices for fastening railway rails upon ties, and has for one of its objects to improve the construction and increase the efficiency and utility of devices of this character.

Another object of the invention is to provide a simply constructed device which may be applied to ties and rails of various forms and sizes and which requires no change either in the tie or in the rail.

Another object of the invention is to provide a simply constructed device whereby the tie which supports the improved device may be removed bodily from beneath the rails without disturbing the remaining ties or the rails.

With these and other objects in view the invention consists in certain novel features of construction as hereinafter shown and described and then specifically pointed out in the claims; and in the drawings illustrative of the preferred embodiment of the invention Figure 1 is a side elevation of a conventional tie having the improved fastening devices applied and with the rails located upon the tie, the rails being in sections transversely. Fig. 2 is a plan view of the parts shown in Fig. 1. Fig. 3 is a detached perspective view of one of the movable rail engaging members.

Corresponding and like parts are referred to in the following description and indicated in all the views of the drawings by the same reference characters.

The improved device may be applied to railway ties of various forms, and it is not desired therefore to limit the device to any specific form of the tie, but for the purpose of illustration the improved device is shown applied to a metal tie represented at 10 and including an upper flange 11. The rails are represented conventionally at 12-13 and are spaced apart the usual distance and bear upon the upper face of the tie.

Bearing upon the flange 11 of the tie externally of the flange of the rail 12 and internally of the flange of the rail 13 are supporting members each including a base por-

tion 14 secured to the tie by rivets or other suitable fastening devices 15. Each of the bases 14 is formed with a rail brace portion 16 which engages against the outer face of the web of the rail 12 and the inner face of the web of the rail 13 as illustrated in Figs. 1 and 2.

Secured upon the flange portion of the tie internally of the rail 12 and externally of the rail 13 are supporting devices including base portions 17 riveted or otherwise secured to the tie as represented at 18. Each of the securing devices is formed with an overhanging projecting portion 19, preferably slightly oblique to the longitudinal plane of the tie with the free edge spaced a considerable distance from the flange of the rail, as shown. Bearing upon the tie between the rails 12-13 and the members 17, and over the flange and against the inner face of the web of the rail 12, and over the flange and against the rail 13, are clamp members each including a base portion 20 bearing upon the rail and beneath the overhanging portion 19 of the member 17. Each of the members 20 likewise includes a rail brace portion 21 which bears against the inner face of the web of the rail 12 and against the outer face of the web of the rail 13. The upper faces of the portions of the members 20 which extend beneath the overhangs 19 are slightly tapered to correspond to the oblique underface of the overhanging portion as represented in Fig. 1. The inner edges of the base portions 17 extend at a slight angle to the transverse plane of the tie while the adjacent edges of the members 20 are correspondingly angular, so that a slight wedge-like action is produced between the members 20 and 17 when the members 20 are forced into position as shown in Figs. 1 and 2. The members 14-16 will bear closely against the rails at one side while the portions 20-21 will bear closely against the rails at the opposite side and will coact with the members 17-18 to produce the required clamping action to firmly and securely support the rails, and will preferably be so constructed as to require a considerable force such as would be imparted by the blows of a sledge or like implement, to cause them to be properly "seated" in position with the ends of the members 20-21 flush with the edges of the flange 11 of the tie.

Rising from each of the portions 20 of the holding devices is a rib 22 through each

one of which a rod 23 is mounted to oscillate, the rod having laterally directed ends 24 which bear against the side edges of the flange 11 of the tie when the projections 5 are turned in downward position, and thus locking the members 20 in position, and when turned in a vertical position, or free from the flanges 11 of the tie, the holding members can be driven from their position 10 and thus releasing the tie from the rails. At the left of Fig. 1 the rod 23 is located with the terminals 24 in their locking position, while at the right the terminals are shown in their upright position with the 15 members 20 released, to illustrate the action of the rods.

With a device thus constructed it will be obvious that the rails are firmly clamped to the ties and prevented from movement 20 both laterally and vertically.

If it is desired to remove the tie it is only necessary to rotate the rods 23 to turn the terminals 24 into upward position as represented at the right of Fig. 1, knock the 25 members 20 loose from their position and remove them, then dig the tamping material from beneath the ties and draw the latter endwise to cause the portions 14-16 to be moved away from the rails. The tie 30 is then dropped at one end to bring the upper end of the portion 16 which has been engaged with the rail 13 below the lower face of the rail 12, when the tie can be removed bodily and without disturbing the other ties 35 or their fastening devices. This is an important advantage in applicants' device and materially increases its efficiency and utility.

The improved device is simple in construction, can be inexpensively manufactured and applied, and operate effectually 40 for the purposes described.

Having thus described the invention, what is claimed as new is:

1. The combination with a railway tie 45 and rail, of a rail holding means engaging with one side of the rail, an abutment on the other side of the rail with its inner edge oblique to the longitudinal plane of the rail, a rail engaging member having an obliquely directed edge engaging the oblique edge of said abutment, said rail engaging member having a bearing rising 50 therefrom, and a member mounted for rotation in said bearing and with laterally directed terminals engageable with the opposite sides of the tie to lock the rail engaging members from movement relative to 55 said abutment and tie.

gaging member from movement relative to said abutment.

2. In a railway rail fastener, a rail base adapted to be rigidly connected to a railway tie in position to bear against a rail at one side, a holding device adapted to be rigidly connected to a railway tie spaced from the rigid rail brace and including an overhanging portion, a movable rail brace 60 adapted to bear against the rail at the other side and extending beneath the overhang of the holding device, and a rod mounted for rotation upon said movable brace and having laterally directed terminals adapted to 65 engage a railway tie and prevent the lateral displacement of the holding device.

3. The combination with a railway tie and the rails supported thereon, of a rail fastener comprising rail braces fastened rigidly to the tie and bearing against the outer face of one rail and the inner face of the other rail, holding devices rigidly fastened to the tie and spaced from the rails, movable rail braces bearing respectively against the 75 inner face of one rail and the outer face of the other rail and beneath the overhang portions of the holding devices, a rod mounted for rotation upon each of said 80 movable rail braces and having laterally directed terminals for engaging the tie and preventing lateral displacement of the movable braces.

4. The combination with a railway tie and rail, of rail holding means engaging 90 with one side of the rail, an abutment on the other side of the rail with its inner edge oblique to the longitudinal plane of the rail and overhanging toward the rail, a rail engaging member having an obliquely 95 directed edge engaging the oblique edge of said abutment and bearing beneath the overhanging portion of the same, said rail engaging member having a bearing rising 100 therefrom, and a member mounted for rotation in said bearing and with laterally directed terminals engageable with the opposite sides of the tie to lock the rail engaging members from movement relative to 105 said abutment and tie.

In testimony whereof we affix our signatures in presence of two witnesses.

ALBERT F. EAGLESTON. [L. S.]
FLOYD C. EAGLESTON. [L. S.]
